(57) **CLAIM**

The ornamental design for a jewelry setting, as shown and described.

DESCRIPTION

FIG. 1 is a perspective view of a jewelry setting according to my invention;

FIG. 2 is a top plan view thereof;

FIG. 3 is a bottom plan view thereof;

FIG. 4 is a front elevational view thereof, the rear elevational view being a mirror image; and,

FIG. 5 is a side elevational view thereof, the opposite side elevational view being a mirror image.

The dashed lines through out the views are for environmental purposes only and form no part of this invention.
